[57] CLAIM

The ornamental design for a dual reservoir sample cup,
as shown and described.

DESCRIPTION

FIG. 1 is a perspective view of a dual reservoir sample
cup, showing my new design;

FIG. 2 is a top plan view thereof;

FIG. 3 is a front elevational view thereof, the rear eleva-
tional view being identical thereto;

FIG. 4 is a side elevational view thereof, the opposite
side being identical thereto; and

FIG. 5 is a bottom plan view thereof.

FIG. 1

FIG. 2

FIG. 3

FIG. 4

FIG. 5
